UNITED STATES PATENT OFFICE.

JAMES HENRY THACKSTON, OF BETHLEHEM CHURCH, VIRGINIA.

TOBACCO-STICK HOLDER.

No. 909,255.

Specification of Letters Patent.

Patented Jan. 12, 1909.

Application filed February 24, 1908. Serial No. 417,376.

To all whom it may concern:

Be it known that I, JAMES H. THACKSTON, a citizen of the United States, residing at Bethlehem Church, in the county of Prince Edward and State of Virginia, have invented 5 certain new and useful Improvements in Tobacco-Stick Holders, of which the following is a specification, reference being had to the accompanying drawings.

10 My invention is an improved tobacco rider or holder for use in supporting tobacco sticks while the tobacco is being cut in the field or after it is stripped and in the barn.

The object of the invention is to provide a 15 simple and practical tobacco stick holder which will be strong, durable, and comparatively inexpensive in construction, which will be convenient to handle and which will effect a great saving in labor.

20 With the above and other objects in view, the invention consists of the novel features of construction and the combination and arrangement of parts hereinafter fully described and claimed, and illustrated in the 25 accompanying drawings, in which—

Figure 1 is a side elevation of my improved tobacco stick holder; Fig. 2 is an end elevation; and Fig. 3 is a detail vertical longitudinal section through one end of the device.

30 The invention comprises an upright supporting frame which may be conveniently moved from place to place in the field, and it preferably comprises two similar end members 1, 2 united by longitudinal rods 3 and 35 having outwardly projecting supporting legs 4 which are spaced apart sufficiently to prevent the frame or holder from being easily overturned. The end members or pieces 1, 2 are preferably in the form of flat metal bars 40 disposed vertically with their flat faces opposing each other and spaced apart by the connecting rods 3. Three of the latter are preferably provided in superposed relation and have their ends reduced to form shoul- 45 ders, and passed through apertures in the bars 2 and upset, as more clearly shown in Fig. 3.

The supporting legs 4 on each end piece or member are preferably formed by bending a piece of metal into substantially semi-circular form and uniting its central portion to the lower end of the bar 2 so that its straight or parallel ends depend.

To permit the device to be easily moved through the field, I preferably provide upon 55 each of the legs 4 a supporting wheel 5 which is journaled upon an axle 6 projecting out-

wardly from the leg 4. Where the field or ground is very rough, and the device must be carried from place to place, the wheels 5 may be removed from their axles, and in order to 60 prevent the latter from coming in contact with the ground, I provide the legs 4 with extended portions or feet 7 which project downwardly below the axles but terminate above the horizontal plane of the lowermost point 65 of the peripheries of the wheels 5, as clearly shown in Fig. 2.

The tobacco sticks are supported upon the device by engaging their ends with V-shaped notches 8 formed in the tops of the 70 upright bars or members 1, 2, or inserting them in triangular-shaped openings 9 formed in the upper portions of said bars or members. I have illustrated two of the openings 75 9 arranged in the same vertical plane in each of said bars or members but it will be understood that any number of them may be provided.

Formed in the intermediate and lower portions of the bars or members 1, 2 are openings 10 which serve to reduce the weight of the device and also for the reception of a temporary connecting rod which may take the place of one of the rods 3, should one of the latter become broken or loose.

In using the invention for holding tobacco sticks while cutting tobacco in a field, the device is drawn or moved along the row as the workman advances and as he cuts the tobacco he hangs it upon one of the tobacco 90 sticks which is supported either in the notches 8 or in the openings 9. The device therefore dispenses with the necessity of the man who cuts the tobacco, or his assistant, holding the stick while the tobacco is being placed thereon and its use results in a great saving in labor. After one tobacco stick has been 95 filled it may be removed from the holder and replaced by an empty one and when the tobacco is not very large, two, three, or even 100 more sticks that have been filled may be supported at the same time by the device. It will be noted that the invention is exceedingly simple in construction so that it is strong and durable and comparatively inexpensive to produce.

Having thus described my invention what I claim is:

1. A tobacco stick holder comprising two vertical end bars formed at their upper ends 110 with notches and adjacent to said upper ends with openings, said openings and notches

being adapted to receive and support tobacco sticks, longitudinal rods connecting said end bars, outwardly and downwardly projecting legs upon the bottom of each of said end bars 5 and supporting wheels journaled upon said legs.

2. A tobacco stick holder comprising upright end bars formed with notches and openings to receive and support tobacco sticks, 10 longitudinal rods connecting said end bars, outwardly and downwardly projecting supporting legs upon the lower end of each of the end bars, spindles upon said legs, wheels re-

movably journaled on said spindles and depending feet upon the legs projecting below 15 the spindles and terminating above the horizontal plane of the lowermost points of the peripheries of said wheels, substantially as and for the purpose set forth.

In testimony whereof I hereunto affix my 20 signature in the presence of two witnesses.

JAMES HENRY THACKSTON.
